US0D1072805S

(12) **United States Design Patent** (10) **Patent No.:** **US D1,072,805 S**
(45) **Date of Patent:** **** Apr. 29, 2025**

(54) **NOTEBOOK COMPUTER**

(71) Applicants: **Han-Tsai Liu**, Taipei (TW);
Jyh-Chyang Tzou, Taipei (TW);
Yao-Hsien Yang, Taipei (TW); **Meng Ju Wu**, Taipei (TW); **Pai-Feng Chen**, Taipei (TW); **I-Hao Chen**, Taipei (TW)

(72) Inventors: **Han-Tsai Liu**, Taipei (TW);
Jyh-Chyang Tzou, Taipei (TW);
Yao-Hsien Yang, Taipei (TW); **Meng Ju Wu**, Taipei (TW); **Pai-Feng Chen**, Taipei (TW); **I-Hao Chen**, Taipei (TW)

(73) Assignee: **COMPAL ELECTRONICS, INC.**,
Taipei (TW)

(**) Term: **15 Years**

(21) Appl. No.: **29/729,672**

(22) Filed: **Mar. 30, 2020**

(51) LOC (15) Cl. **14-02**

(52) U.S. Cl.

USPC **D14/315**; D14/320

(57) **CLAIM**

The ornamental design for a notebook computer as shown and described.

DESCRIPTION

FIG. 1 is a perspective view of a notebook computer showing a first embodiment of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the notebook computer of FIGS. 1-7 shown in an alternate position;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of a notebook computer showing a second embodiment of our new design;

FIG. 16 is a front view thereof;

FIG. 17 is a rear view thereof;

FIG. 18 is a left side view thereof;

FIG. 19 is a right side view thereof;

FIG. 20 is a top view thereof;

FIG. 21 is a bottom view thereof;

(Continued)

FIG. 22 is a perspective view of the notebook computer of FIGS. 15-21 shown in an alternate position;

FIG. 23 is a front view thereof;

FIG. 24 is a rear view thereof;

FIG. 25 is a left side view thereof;

FIG. 26 is a right side view thereof;

FIG. 27 is a top view thereof; and,

FIG. 28 is a bottom view thereof.

The dashed broken lines shown in the drawings illustrate portions of the notebook computer that form no part of the claimed design. The dot-dash broken lines define the bounds of the claimed design and form no part thereof.

1 Claim, 24 Drawing Sheets

(58) Field of Classification Search

CPC G06F 1/1616; G06F 1/203; G06F 1/1647;
G06F 1/1649
